UNITED STATES PATENT OFFICE.

GUIDO FORNACA, OF TURIN, ITALY, ASSIGNOR TO F. I. A. T., A CORPORATION OF NEW YORK.

COMBUSTION-ENGINE.

1,146,788.

Specification of Letters Patent. Patented July 20, 1915.

Original application filed January 5, 1911, Serial No. 600,854. Divided and this application filed April 8, 1913. Serial No. 759,627.

To all whom it may concern:

Be it known that I, GUIDO FORNACA, a subject of the King of Italy, residing at Turin, Province of Piedmont, Italy, have invented 5 certain new and useful Improvements in Combustion-Engines, of which the following is a full, clear, and exact specification.

This invention relates to combustion engines and has especial reference to improvements in the construction and arrangement 10 of the parts of a combustion engine, more especially intended for automobiles, whereby the parts will be simplified and rendered more accessible, and also an improved mode 15 of operation secured.

The object of the invention is to provide an improved driving gear for the cam shaft, magneto and a pump, whereby the parts are more compact, and increased simplicity and accessibility secured.

The invention with respect to the various parts thereof will be more fully understood in connection with the description of the accompanying drawings, wherein—

25 Figure 1 is an elevation, seen from the left, of an engine embodying the invention; Fig. 2 is a sectional view showing the interior of the engine; and Fig. 3 is an end elevation partly in section showing the arrangement of the various shafts.

30 1 represents the frame of the machine, 2 the radiator, supported near the bottom by trunnions 3 and flexibly supported at the top as through the hose coupling 4 leading from 35 the water jacket outlet pipe 5.

6 is a radiator discharge pipe leading to the pump casing 7 formed in the base 30, and discharging by pipe 8 into the lower front portion of the water jacket casing 9.

40 11 is the inlet manifold pipe, 12 the exhaust pipe, 13 a water discharge port leading to passage 14 in removable water jacket cover 15, and thence connected to radiator inlet pipe 5.

45 18, 19, are water baffle plates and strengthening ribs.

Charge inlet pipe 11, branches by pipe 20 to inlet chambers 21, controlled by inlet valves 22.

50 111 is a mixing chamber, connected by pipe 113 to inlet pipe 11, and 123 is an arm for operating the usual throttle valve.

24 are exhaust valves which open into chambers 25, and thence connected to ex-

haust pipe 12, which is preferably within the 55 water jacket.

The cylinder casting, open at the bottom, is mounted on a base 30, having holes therethrough for the various connecting rods, the base having transverse arms 31 at each end 60 which are fastened to the frame in the usual manner. The crank shaft 32 carries a flywheel 33 at the rear end and is mounted to be turned by starting crank 34 to start the engine in the usual manner. The crank 65 shaft is what is known as a three bearing crank shaft; that is, it has a bearing 35 at each end, and an intermediate bearing 36 between the pairs of cylinders, it being understood that the invention is not restricted to a motor having four cylinders, nor to any particular number of bearings. The base 30 is constructed to withstand the strains from the crank shaft and carries complete 70 the bearings 35, and also the other bearings 75 and shafts. In order to protect the crank shaft, a crank case or bottom cover 37 is detachably secured to the bottom of the base as by bolts 370 and this crank case is formed to provide an oil reservoir which can be 80 filled through pipe 38 and from the bottom of which the oil is taken by pipe 39 to an oil pump 40. (See Fig. 1). From the oil pipe a suitable oil duct leads through an oil gage 41, and thence through a valve controlled by 85 push pin 42 to the various parts of the engine including the cylinders and the crank shaft bearings. In order to make the external oil ducts as few as possible, and thereby avoid a multiplicity of pipe connections, the 90 base is formed at one side with oil duct 45, which is connected with the bearings 35 and 36 through tubes in the struts 47, at the ends and middle of the base casting. By this arrangement, a proportionate supply of oil 95 is supplied to the various bearings according to the speed of the engine, and also it will be seen that the pistons, crank pins and bearings will be lubricated by the splash from the oil contained in the detachable crank 100 case.

I will now describe the arrangement and operation of the shafting system in this invention, whereby accessibility of the various parts necessary to be included is secured and also compactness and simplicity in arrangement obtained.

It is desirable to simplify and reduce the

external parts of an engine as much as possible, and to enable the absolutely essential external parts to be accessible and capable of being removed where necessary. This is especially desirable of the magneto, which should be accessible and removable with the least amount of trouble, and the external appearance of the engine is improved by removing the manifold pipes, the oil feeds, and whatever other parts possible, or casting them so that they will not be subject to damage or disarrangement. With these objects in view, I propose to mount the magneto at one end of the engine, preferably 10 the front, and to arrange its driving shaft transversely of the engine, the water pump preferably being on the other end. As herein shown, I have mounted the oil pump at the rear end of the half speed cam shaft, 15 which latter shaft operates both sets of valves.

The crank shaft 32 carries at its forward end a gear 50, which meshes with a gear 51 splined to the end of cam shaft 52, the gear 25 51 having a front bearing 53. At the center of the base casting 30 the cam shaft has ordinary bearings 54. Rigid with the cam shaft 52 is a worm pinion 35 which meshes with a similar pinion 56 carried by a trans- 30 verse shaft 57 (see Figs. 2 and 3), this shaft 57 having a thrust bearing 58 journaled in the forward end of the base casting 30. The gear 51 is twice the diameter of gear 50, so that the cam shaft 52 will be driven at one 35 half of the speed of the crank shaft 32, and the pinion 55 is twice the diameter of pinion 56, so that shaft 57 will be driven at the same speed as the main shaft 32, though of course any other ratio could be employed. 40 60 represents the magneto which is herein shown as mounted on the right forward corner of the base 30 immediately adjacent the forward cylinder, and it is connected to be driven by shaft 57 through a universal 45 or Oldham coupling 61. From the distributor 62 the wires 63 lead to the corresponding spark plugs 64 of the various cylinders, the wires being carried in the conduit 65 supported on the cover 15 or in any 50 other suitable manner. From the engine casting or separate spark plugs the usual return connection to the magneto is provided. The shaft 57, as will be seen from Fig. 3, is supported by webs 66 cast in the 55 base 30, the center web also extending down to support the end bearing 35 for the main shaft, the base being extended to form a cover inclosing the pinions 55, 56. At the opposite end of the shaft 57, there is mounted 60 in a bearing hanger 68, carried by the base 30, a pump shaft 69, connected at one end with the shaft 57 and at the other end having the pump rotor 70 revolving in the pump casing 71. The pump casing 71 is 65 connected with the discharge pipe 6 leading

from the radiator and peripherally discharges the water into pipe 8, connected as before stated to the water jacket.

The inner end of the shaft 52 drives an oil pump, such as a well known pair of meshing gears rotating in the oil pump casting 40 and operating to draw oil from pipe 39 and force it through oil ducts aforesaid to gage 41, and thence to the various bearings.

By this invention, a simple and accessible arrangement of the auxiliary shafts of a combustion engine is provided. The several driven parts are all normally protected, yet can be easily removed or examined when necessary. Moreover, lost motion between the crank and cam shafts is reduced, and quietness in operation secured.

By this invention, a simple and accessible arrangement of the auxiliary shafts of a combustion engine is provided. The several driven parts are all normally protected, yet can be easily removed or examined when necessary. Moreover, lost motion between the crank and cam shafts is reduced, and quietness in operation secured.

This application is a division of my application Serial No. 600,854, Combustion engine, filed January 5, 1911, and features described and shown herein, but not claimed, are reserved in said application, or other divisions thereof.

Various modifications and changes may be made in the specific construction described without departing from the scope of the annexed claims.

Having thus described my invention, I declare that what I claim as new and desire to secure by Letters Patent, is:—

1. The combination with an engine base casing, of cylinders mounted thereon, a crank shaft journaled longitudinally of and within said casing, a cam shaft journaled within said casing parallel to said crank shaft and geared thereto, a transverse shaft journaled within the forward end of said casing and driven by said cam shaft gearing, a pump chamber formed in one corner of said casing, a magneto mounted on the opposite corner of said casing, a movable pump element carried by one end of said transverse shaft, and a driving connection between the other end of said transverse shaft and the magneto.

2. The combination with an engine base adapted to be supported on a vehicle frame, of cylinders mounted thereon, a crank shaft journaled longitudinally of the base, a cam shaft journaled parallel to said crank shaft and geared thereto to be driven at a reduced speed, a transverse shaft journaled to the forward end of said base and separately geared to be driven at an increased speed by said cam shaft gearing, a magneto, and a driving connection between said magneto and said transverse shaft.

3. The combination with an engine base adapted to be supported on a vehicle frame, of cylinders supported on said base, a crank shaft, a cam shaft parallel thereto, a magneto and a water pump carried by said base, said cam shaft being driven by said crank shaft, and said magneto and water pump being driven by said cam shaft gearing.

4. The combination with an engine base adapted to be supported on a vehicle frame, of cylinders supported on said base, a cam shaft driven by said crank shaft and journaled parallel therewith, a transverse shaft driven by said cam shaft gearing and journaled at the forward end of said base, a rotary pump and a magneto carried by said base, the rotary elements of said pump and 10 said magneto respectively being coupled to opposite ends of said transverse shaft.
5. The combination with a base, cylinders and valve mechanism, of a crank shaft, a cam shaft parallel thereto, spur gearing at 15 one end for directly driving said cam shaft at one-half speed, a spiral gear carried by said cam shaft adjacent said spur driving gear, a transverse shaft outside of the forward cylinder, a spiral gear thereon driven
- by said first spiral gear at twice the speed, 20 a magneto and a distributor detachably coupled at one end of said transverse shaft, and a pump detachably coupled at the opposite end.
6. The combination with an engine comprising a plurality of cylinders, a crank shaft, a cam shaft parallel to said crank shaft and geared thereto, an oil pump driven from said cam shaft, a transverse shaft 25 geared to said cam shaft, and a magneto and 30 a water pump driven by said transverse shaft.

In testimony whereof I affix my signature, in presence of two witnesses.

GUIDO FORNACA.
